UNITED STATES PATENT OFFICE.

VICTOR H. JENNINGS, OF WORCESTER, MASSACHUSETTS, ASSIGNOR TO UNIVERSAL PATENTS COMPANY, OF WOONSOCKET, RHODE ISLAND, A CORPORATION OF RHODE ISLAND.

WOVEN POCKETED CARRIER AND METHOD OF MAKING THE SAME.

1,293,791.

Specification of Letters Patent.

Patented Feb. 11, 1919.

Application filed August 17, 1917. Serial No. 186,671.

To all whom it may concern:

Be it known that I, VICTOR H. JENNINGS, a citizen of the United States, residing at Worcester, in the county of Worcester, State 5 of Massachusetts, have invented a certain new and useful Improvement in Woven Pocketed Carriers and Methods of Making the Same, of which the following is a specification, reference being had therein to the 10 accompanying drawings.

The invention relates to woven pocketed carriers and the manufacture thereof; and applies more particularly in the case of pocketed carriers of the general class having 15 a plurality of pockets side by side, respectively provided with individual covers or flaps which are movable independently of one another to enable any one of the pockets to be closed or opened at will. Such class 20 includes cartridge carriers, as well as various other carriers having special adaptations.

Heretofore, in the case of carriers of the general class mentioned, the individual covers or flaps usually have been made as separate articles and then respectively attached to the carrier. The present invention produces a plurality of covers or flaps in a connected series, all being integral laterally 30 projecting portions of a web which either is itself an integral portion of a pocket-web or is produced separately and attached to the pocket-web in making up a carrier.

The invention finds useful application, 35 also, in the manufacture of carriers which in their completed state comprise single pockets.

General objects of the invention are to facilitate the manufacture of carriers having 40 pockets provided with covers or flaps; also, to facilitate the manufacture of carriers having a plurality of pockets side by side, each provided with its own independently 45 movable cover or flap, as well as to reduce the number of manual operations required to be performed in manufacturing the said carriers, and to simplify such operations. A further object of the invention is to combine covers or flaps such as aforesaid

with the pockets of a group or series in the 50 process of weaving, instead of subsequent thereto as usual heretofore in the case of carriers of the multiple pocket type having individual covers or flaps.

The invention is illustrated by the accompanying drawings, in which latter,—

Figure 1 is an isometric view of a portion of a multiple-pocketed carrier embodying features of the invention, with the pocket-covers or flaps integral with the pocket-backs in this instance.

Fig. 2 is an isometric view of a portion of a pocket-web such as is used in the production of a carrier like that of Fig. 1, the two plies of the cover or flap-forming portions of 60 the said web being in an uncut state.

Figs. 3 and 4 are views in cross-section on lines 3—3, and 4—4, respectively, of Fig. 2.

Fig. 5 is an isometric view of a portion of a cover or flap web woven separately, for 70 application to a pocket-web in making up a carrier, the two plies being in an uncut state.

Figs. 6 and 7 are views in cross-section, on line 6—6 and 7—7, respectively, of Fig. 5.

Fig. 8 is an isometric view of a portion of 75 the web of Fig. 5, after the cutting of the plies and the hemming of the sides of the covers or flaps.

Fig. 9 is an isometric view of a portion of a pocketed carrier embodying the cover or 80 flap web of Figs. 5 to 8.

Having reference to Fig. 1, the latter shows several of the pockets 1, 1^a, etc., of a multiple-pocket woven carrier, and intervening portions 2, 2, etc., of the supporting-band or body-web. 3, 3, etc., are the individual covers or flaps of the said pockets. 4 and 5 are fastening devices of usual character, applied in connection with the pocket-fronts and covers or flaps, and adapted to 90 secure the said covers or flaps in closed condition.

The covers or flaps 3, 3, etc., of Fig. 1 are integral upward continuations of the pocket-backs. For the production of the carrier of 95 Fig. 1 the pocket-web shown in Figs. 2, 3 and 4 is employed. Such pocket-web is woven with the pockets 1, 1^a, etc., and with

an upward extension of its back above the tops of the said pockets, in the form of two plies or cloths *a* and *b*, of a width corresponding to the length of a cover or flap from its point of connection with a pocket-back to the edge of its free extremity.

At alternate pockets, as 1, 1, the portions *a'*, *a'*, of the ply or cloth *a* are integrally joined to the pocket-backs 1^b, 1^b, (see Figs. 10 2 and 3) as integral continuations thereof transversely of the pocket-web, but the ply or cloth *b* is unconnected with the pocket-back at each of such pockets and has a selvage-edge *b'*, Fig. 3, extending along adjacent the mouth of the pocket. At each intervening pocket, as 1^a, the conditions are reversed, (see Figs. 2 and 4) the portions *b'* of the ply or cloth *b* being integrally joined to the pocket-back 1^c as integral continuations thereof transversely of the pocket-web, and the ply or cloth *a* being unconnected with the said pocket-back, and having a selvage-edge *a'* extending along the mouth of the pocket. Thus, the ply or cloth *a* is integrally joined with the pocket-backs of alternate pockets, namely those marked 1, 1, and not with those of the intervening pockets 1^a, 1^a, while the ply or cloth *b* is integrally joined with the pocket-backs of the intervening pockets 1^a, 1^a, and not with those of the pockets 1, 1.

To form the covers or flaps, the top ply or cloth *a* is cut across from its outer selvage edge to its selvage edge *a'* mid-way between successive pockets 1, 1; that is to say, at a point *x*, Fig. 2, substantially in line with the middle of the width of each of the intervening pockets 1^a. The under ply or cloth *b* is cut across from its outer selvage edge to its selvage edge *b'* midway between successive pockets 1^a, 1^a; that is to say, at a point *y* substantially in line with the middle of the width of each of the alternate pockets 1. This cutting operation separates the two plies or cloths *a*, *b*, into flap-extensions forming continuations of the pocket-backs of the respective pockets 1, 1^a. Each of the said flap-extensions has oppositely-projecting lateral wings having upper and lower selvaged edges. The said wings are folded over upon themselves and stitched to form the hems 6, 6.

The cover or flap web of Figs. 5, 6, and 7, woven separately and without pockets, designed to be cut and finished as shown in Fig. 8, and to be applied to a pocketed web as shown in Fig. 9, is produced with an attaching lip or margin *c* along one side thereof, combined with a main portion that is woven double, *i. e.*, composed of two plies or cloths *d* and *e* similar to the plies *a* and *b* of Figs. 2, 3 and 4. Alternate portions *d'*, *d'*, of the top ply or cloth *d* are integral

continuations, transversely of the web, of the lip or margin *c*, as shown by Figs. 5 and 6, while the intervening portions *d'*, *d'*, are formed with selvage edges *d²*, *d²*, alongside the said lip or margin, as shown by Figs. 5 and 7. Intermediately of the portions *d'*, *d'*, of the ply or cloth *d*, portions *e'* of the under ply or cloth *e* are integral continuations, transversely of the web, of the lip or margin *c*, while as shown by Fig. 6 the portions *e³* of said under ply or cloth *e* intervening between the portions *e'*, *e'*, are formed with selvage edges *e²* alongside the lip or margin *c*.

After the web of Figs. 5, 6 and 7 has been cut and its flap-extensions have been hemmed substantially as in the case first described, it appears as in Fig. 8. The pocket web 10, Fig. 9, with which the finished web of Fig. 8 is combined is woven with a housing slit 11 into which the lip or attaching margin *c* of the latter web is inserted, and within which it is made secure by suitable fastenings, preferably stitches 12.

From the foregoing it will be perceived that in conformity with one part of the invention, a web which either is itself an integral portion of the pocket-web or is separately produced and then attached to the latter in making up a carrier as aforesaid is woven double, that is to say in two plies or cloths, for a portion of the width thereof. These two plies or cloths are so conjoined with the remainder of the width of the web that one ply or cloth forms the covers or flaps of alternate pockets of the series, after such ply or cloth has been cut across mid-way between such pockets, while the other ply or cloth forms the covers or flaps of the remaining pockets of the said series after having been cut across midway between the latter pockets. The side-edges of the respective covers or flaps are finished off by being turned or hemmed.

The invention enables the covers or flaps to be made somewhat wider than the pockets, as shown, so that when they are closed down over the pockets their lateral portions project at the sides of the latter, thereby more effectually excluding dust and moisture and thus affording better protection to the pocket-contents.

A multiple-pocket organization produced in either of the ways described herein may be cut up into groups of pockets of any usual or approved number, or into detached single pockets.

The invention may be carried into effect by producing the web upon a double shuttle-loom, in which case the selvage-edges *a²* and *b'*, or *d²* and *e²*, adjacent the mouths of the respective pockets will be entirely distinct and independent from the opposing portions

of the web. The invention may be carried into practical effect, also, in a single shuttle-loom by so conducting the weaving that although the said selvage-edges shall be connected at intervals by portions of weft or filling to the opposing portions of the web they may be disconnected from the said opposing portions of the web subsequent to the weaving, by cutting the said connecting portions of weft or filling without impairment of the selvages or of the said opposing portions of the web.

The hems 6, 6, serve to reinforce the side-margins of the covers or flaps.

15 What is claimed as the invention is:—

1. The improved carrier - web having a plurality of pockets and two cover or flap producing plies or cloths, with one ply or cloth integrally joined with alternate pockets but distinct at the intervening pockets, and with the other ply or cloth integrally joined with the said intervening pockets and distinct at the said alternate pockets.

2. The improved carrier - web having a plurality of pockets and two cover or flap producing plies or cloths, with one ply or cloth integrally joined with alternate pockets but selvage-edged at the intervening pockets, and with the other ply or cloth integrally joined with said intervening pockets and selvage-edged at the said alternate pockets.

3. The improved web having an upward extension comprising two plies or cloths, each having successive portions which alternately are integral with the body of said web and distinct therefrom, with the integral portions of one ply or cloth alternated with those of the other.

4. The improved web having an upward extension comprising two plies or cloths, each having portions which are continuous and integral with the body of the web and intervening portions which are selvage-edged adjacent such body, with the continuous and integral portions of one ply or cloth alternated in order of succession with those of the other.

5. The method of manufacturing woven pocket - covers or flaps which consists in weaving a web double, *i. e.*, in two plies or cloths for a portion of the width thereof, with the said plies or cloths alternately conjoined with the remainder of said width, whereby one ply or cloth will form the covers or flaps of alternate pockets of a series after such ply or cloth has been cut across midway between such pockets, while the other ply or cloth will form the covers or flaps of the remaining pockets of the said series after having been cut across midway between the latter pockets, then cutting the plies or cloths in the manner described and thereby separating the covers or flaps from one another, and finishing the side - edges of the respective covers or flaps.

thereby separating the covers or flaps from one another, and finishing the side-edges of 65 the respective covers or flaps.

6. The method of manufacturing woven pocket - covers or flaps which consists in weaving a web double, *i. e.*, in two plies or cloths for a portion of the width thereof, 70 with the said plies or cloths alternately conjoined with the remainder of said width, whereby one ply or cloth will form the covers or flaps of alternate pockets of a series after such ply or cloth has been cut 75 across midway between such pockets, while the other ply or cloth will form the covers or flaps of the remaining pockets of the said series after having been cut across midway between the latter pockets, then cutting the 80 plies or cloths in the manner described and thereby separating the covers or flaps from one another, and finishing the side-edges of the respective covers or flaps by hemming the same.

7. The method of manufacturing woven pocket - covers or flaps which consists in weaving a web with a series of pockets and double, *i. e.*, in two plies or cloths for a portion of its width, with the said plies or 90 cloths alternately conjoined with the remainder of said width, whereby one ply or cloth will form the covers or flaps of alternate pockets of the series after such ply or cloth has been cut across midway between 95 such pockets, while the other ply or cloth will form the covers or flaps of the remaining pockets of the said series after having been cut across midway between the latter pockets, then cutting the plies or cloths in 100 the manner described and thereby separating the covers or flaps from one another, and finishing the side - edges of the respective covers or flaps.

8. A multiple - pocketed woven carrier 105 having a plurality of individual covers or flaps for the pockets, respectively exceeding in width the width of the pockets, said covers or flaps all being integral projecting portions of a continuous web, and having 110 side-wings woven with upper and lower selvaged edges.

9. A woven carrier comprising a multiple-pocketed pocket-web having individual independently-movable pocket-covers or flaps 115 which are integral projecting portions of the pocket-web itself and are formed with side-wings having upper and lower selvaged edges, said pocket - covers or flaps respectively exceeding in width the width of the 120 pockets.

10. A multiple - pocketed woven carrier having a plurality of individual covers or flaps for the pockets, said covers or flaps all being integral projecting portions of a continuous web and having side-wings that are 125

woven with upper and lower selvaged edges and formed into reinforcing hemmed side-margins.

11. A woven carrier comprising a multiple-pocketed pocket-web having individual independently-movable pocket-covers or flaps which are integral projecting portions of the pocket-web itself and having side-wings that are woven with upper and lower

selvaged edges and formed into reinforcing hemmed side-margins.

In testimony whereof I affix my signature in presence of two witnesses.

VICTOR H. JENNINGS.
